(57) **CLAIM**

The ornamental design for a ring, as shown and described.

DESCRIPTION

FIG. 1 is a top, front, left side perspective view of a ring showing my new design;

FIG. 2 is a front elevational view thereof;

FIG. 3 is a back elevational view thereof;

FIG. 4 is a right side elevational view thereof, the left side elevational view being identical thereto;

FIG. 5 is a top plan view thereof; and,

FIG. 6 is a bottom plan view thereof.

The broken lines shown in the drawings illustrate portions of the ring that form no part of the claimed design.
